[57] CLAIM

The ornamental design for a combined laptop computer
with cellular telephone and carrying case therefor, as
shown and described.

DESCRIPTION

FIG. 1 is a front elevational view of the combined laptop
computer with cellular telephone and carrying case
therefor showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The pattern shown in FIGS. 5 and 7 represents a wood
grain.

FIG. 1
